MECHANICAL MOVEMENT.

1,231,062.

Specification of Letters Patent. Patented June 26, 1917.

Application filed December 8, 1912. Serial No. 734,669.

To all whom it may concern:

Be it known that we, RICHARD H. PIETZSCH, citizen of the United States, and resident of Philadelphia, county of Philadelphia, and State of Pennsylvania, and WALTER HURLEMAN, a citizen of the United States, and resident of Camden, county of Camden, State of New Jersey, have invented an Improvement in Mechanical Movements, 10 of which the following is a specification:

The object of our invention is to provide a construction of mechanical movement for converting continuous rotary movement into intermittent rotary movement such as is required for intermittently feeding photographic films in that class of machines employed in moving picture exhibitions, the device being so constructed that the means for locking the intermittently rotated part in 20 fixed position between each movement is independent of the means for imparting the rotary impulses, whereby wear of the means for imparting the intermittent movement will not cause lost motion or permit of vibration of the driven part. By providing for the locking of the driven part for the period between each forward movement, by means independent of the means which imparts the intermittent movement, very great 25 accuracy of movement may be had, and when employed in a moving picture machine, much of the vibration of the image will become eliminated.

While our invention is especially adapted 35 for use in moving picture machines, we do not confine its use to any particular use, but refer to this as an example of its special utility as in such machines great accuracy is desirable to insure proper superimposing of 40 the images and avoidance of objectionable vibration.

Our invention consists of certain features of construction which are fully described hereinafter and more particularly defined in 45 the claims. Our improvements will be better understood by reference to the drawings, in which:

Figure 1 is a perspective view of a mechanical movement embodying our invention; Fig. 2 is a front elevation of the same with the driving and driven shafts broken away; Fig. 3 is a transverse section on line $x-x$ of Fig. 2, illustrating details of the driving cam drum; Fig. 4 is an elevation

corresponding to Fig. 2, but showing a modified form of our invention; and Fig. 5 is a cross section on line $y-y$ of Fig. 4 illustrating the surface formation of the driving cam drum.

2 is the continuously rotating or power shaft; and 3 is the intermittently rotated or driven shaft. The driven shaft 3 is intermittently rotated from the continuously rotating driving shaft 2 by mechanical devices which embody our improvements and will now be described. Secured to the driven shaft 3 is a wheel 4 which is provided with four slotted portions 6 in its periphery, said slotted portions being equally spaced about the perimeter of the wheel. The circumferential surface of this wheel 4 is also provided with four radially arranged steel pins 5 which are likewise equally spaced about the wheel and respectively intermediate of the slotted portions 6. Secured to the driving shaft 2 is a cam drum 8, said drum having a curved circumferential face 9 and inclined guide edges 10 at each side thereof. This cam drum 8 is further provided with a cam groove 12 arranged transversely and obliquely to its outer face at one place in its circumference, and said cam groove blending into the inclined guide edges 10 by the curved portions 13 and 14. In addition to the parts just described, the cam drum 8 is further provided with a radial locking flange 19 extending circumferentially around it at its middle portion with the exception of a short distance on each side of the transverse cam groove 12, said locking flange terminating at its ends 20 with a more or less pointed or knife-edged shape; and it is also provided with the cam portions 15 and 16, as extensions of the inclined guide edges 10 of the drum, the cam 15 being arranged upon the drum on the side opposite to the entrance part 13 of the cam groove 12, and the cam 16 being upon the side of the drum opposite to that having the part 14 of the cam groove 12.

By reference to Fig. 2, it will be seen that the driven wheel 4 fits the outer surface of the drum and has two of its radial pins 5 in operative relation with the opposite inclined edges 10 of the drum 8. It will also be observed that the radial locking flange 19 snugly fits the slotted portion 6 of wheel 4

which is intermediate of the two radial pins aforesaid. In this way, the wheel 4 is doubly locked against rotary movement, but the accuracy for holding the wheel 4 against 5 the slightest rotary motion is dependent upon the radial locking flange 19, and its engagement with the slotted portion 6. The pins 5, while held against movement in either direction, need not make a tight fit 10 with the inclined edges 10, but coöperate with said edges more for the purpose of causing the pins to be properly actuated by the cam groove 12, 13, 14, when the drum 8 is rotated. Still referring to Fig. 2, it will 15 be seen that if the drum 8 be rotated so that the cam groove 12 is moving upward, the part 13, leading to the cam groove, will be brought into contact with the left-hand pin 5 at the same time that the right-hand pin 20 5 is reached by the cam 15. At this same moment, the end 20 of the radial locking flange will have passed beyond and out of the lower slot 6 of the wheel 4, and thereby unlocked it. A further movement of the 25 cam drum 8 will, by the action of the cam 15, cause the wheel 4 to be slightly rotated to bring the left-hand pin 5 into complete engagement with the cam groove 12, and a continuation of this motion will cause the 30 cam groove 12 to so operate upon the pin 5 that a quarter of a revolution will be given to the wheel 4 and its shaft 3 before the other end 20 of the radial locking flange 19 is brought into locking engagement with the 35 next or left-hand slot 6 of the wheel 4. As soon as this takes place, the wheel 4 is positively locked against any vibration, and the drum 8 may be given almost a full revolution before the next intermittent action is 40 given to the wheel 4, this latter movement being a repetition of the one just described. It will be observed that the operative portion of the cams 15 and 16 upon the pins terminates shortly after it begins, as the object 45 is only to require the pins to properly enter the cam slot 12, but I have also shown these cam portions 15 and 16 extended so as to provide cam portions 18 and 17 respectively, the same acting as cams upon the pins 5 to assist or positively insure the pins entering the cam groove 12. It will be seen by reference to Fig. 2 that if the cam drum is rotated as before, the left-hand pin 5 will 50 enter between the parts 13 and 17 and be positively forced to enter the cam groove 12 at the same time that the right-hand pin 5 is being actuated by the cam 15 to assist in such entrance of the left-hand pin. As the parts are drawn, the drum 8 may be rotated 55 in either direction to intermittently rotate the shaft 3 in one direction or in the opposite direction, as may be required. It is manifest, however, that if the only one direction of rotation is required, the cam 16 60 and the part 18 may be omitted, if so de-

sired. It is also evident that both of the parts 17 and 18 may be omitted, although we prefer to use them, as there is more positiveness to the apparatus since action is given upon both pins 5 to impart the initial movements to the shaft 3 and its wheel 4.

70

It will be understood that while we have shown four pins and four slotted portions for the wheel 4, this number may be changed, as more of such parts may be employed, and likewise, three such pins and slots might be employed by proper proportioning of the drum, and we therefore do not restrict ourselves in this respect. It is equally evident that while only one of the cam grooves 12 and its associated parts are employed, any number of these parts may be used if so desired, as the more of them the more rapidly will the intermittent movements be imparted to the shaft 3 for a given 80 number of revolutions of the shaft 2. As shown, one revolution of the shaft 2 imparts one intermittent movement to the shaft 3, but it is evident that the drum 8 may be of any size and have as many duplications of 85 the parts shown as desired, so that one revolution of the shaft 2 may make any number of intermittent movements of the shaft 3 that may be desired, said changes in no way affecting the general construction and principle of operation of our invention. In the 90 particular illustration in Fig. 1, we have shown the intermittently driven shaft 3 as provided with a sprocket drum 7 which is that portion of a moving picture machine 95 which imparts an intermittent feeding motion to the picture film, but we in no way limit our invention to use in connection with such drum, as the driven shaft 3 may be employed for any ordinary purpose where a 100 positive and accurate intermittent rotary movement is required.

100

In Figs. 4 and 5, we have shown a modified form of our invention, in which, instead of the slots 6 in the periphery of the wheel 4, we provide ribs 6^a, and instead of employing the radial locking flange 19 on the cam drum 8, we show a circumferential locking groove 19^a widened on each side of the cam groove 12, as indicated at 19^b. This 110 is practically a reversal of the parts 6 and 19 of Fig. 2, and it operates in the same manner, but in this case the clearance spaces 19^b must be provided to allow the projections 6^a to move transversely when the pin 5 is 115 being operated by the cam groove 12. The depth of these grooved portions will be clearly understood by reference to Fig. 5, the same being taken on line y—y of Fig. 4. It is also to be understood that while the outer 120 circumference of the drum 8 is more or less grooved, as at 9, to fit the curvature of the perimeter of the wheel 4, this is not at all necessary to the operativeness of the invention. It is, however, preferable from a me- 130

125

chanical point of view. We do not confine ourselves in any manner to the shape or form of the radial locking flange 19, as this may be of any shape found most suitable, but we prefer the rectangular form shown in the drawings.

From the foregoing description, it will be understood that the locking flange 19, co-operating with the slotted portion 6, is wholly independent in its action upon the wheel 4 of the operative means comprising the cam slot 12 and the pins 5 for imparting the intermittent rotary motion to the said wheel. In other words, the radial flange 19 does not act in any manner to produce a rotary motion of the wheel 4 or its shaft 3, and for this reason, we refer to it as being means independent of the means for imparting the rotary impulses, and it is because 20 of this particular means that the wear upon the pins and radial flanges 10 will not in any way interfere with the steadiness of the shaft 3 and its wheel 4 when the latter is in locked position under the control of the radial 25 flange 19. As the radial flange 19 always revolves in the same plane, it is evident that very little wear will come upon it or the sides of the slot 6 of the wheel 4, and as the wheel may be made of hardened steel 30 and the radial flange may be of equally hard material, it is evident that these parts will coöperate for an exceedingly long time without any material wear such as would produce objectionable lost motion. The wedge-shaped ends 20 of the radial locking flange insures the accurate entering into the slots 35 and removes any possibility of accidental binding of the parts.

While the construction shown in Figs. 1, 40 2 and 3 is that which we have preferred in practice, we do not limit ourselves to the details, as these may be modified without departing from the spirit of the invention.

Having now described our invention, what 45 we claim as new and desire to secure by Letters Patent, is:—

1. In a mechanical movement for converting continuous rotary motion into intermittent rotary motion, the combination of a rotatable driving shaft, a rotatable driven shaft, a drum on the driving shaft having a transverse cam on its periphery arranged obliquely to the axis of the shaft and also having a circumferential guide extending 50 about the drum except adjacent to that portion having the cam, and a wheel on the driven shaft having radial portions about its perimeter for engaging the cam of the drum and also having a guide portion in its perimeter intermediate of the radial portions for engaging the circumferential guide of the drum to intermittently lock the driven shaft and its wheel against rotation.

2. In a mechanical movement for converting 55 continuous rotary motion into intermit-

tent rotary motion, the combination of a rotatable driving shaft, a rotatable driven shaft, a drum on the driving shaft having a transverse cam groove arranged obliquely to the axis of the shaft and having a cam projection relatively positioned with respect to the entrance end of the cam groove, and a wheel secured to the driven shaft having a plurality of radial pins arranged to respectively be acted upon by the cam groove 70 and cam projection and in which the cam projection acting upon one pin causes a rotation of the wheel to bring a pin thereof into engagement with the cam groove, and locking means separate from the cam portions and pins for locking the driven shaft and its wheel against movement when the cam groove is not acting upon the pins.

3. In a mechanical movement for converting continuous rotary motion into intermittent rotary motion, the combination of a rotatable driving shaft, a rotatable driven shaft, a drum on the driving shaft having a transverse cam groove arranged obliquely to the axis of the shaft and with one wall 85 extended to provide a circumferential entrance into the groove and having a cam projection relatively positioned with respect to the entrance end of the cam groove but on the side of the drum most distant from the 90 entrance of the cam groove, and a wheel secured to the driven shaft having a plurality of radial pins arranged to respectively and simultaneously be acted upon by the cam groove to start the rotation of the wheel and whose further rotation is accomplished by the cam groove, and locking means separate from the cam portions and pins for locking the driven shaft and its wheel against movement when the cam groove is not acting 100 upon the pins.

4. In a mechanical movement for converting continuous rotary motion into intermittent rotary motion, the combination of a rotatable power shaft, a rotatable driven 110 shaft, a drum on the power shaft having a transverse cam groove therein, and also having a circumferentially inclined guide edge forming a continuation of said cam groove, a locking flange radially disposed on said 115 drum and partially encircling said drum, a wheel secured to the driven shaft having a plurality of slots therein, each adapted to receive said flange at certain times, and a radially disposed pin between each pair of 120 slots and projecting beyond the periphery of said wheel, said pins being adapted to ride upon said inclined edge of said drum, whereby one of said pins is guided into and through said cam groove to impart a partial 125 rotation to said wheel.

5. In a mechanical movement a driving member, comprising a peripherally grooved wheel provided with chamfered edges and having a sinuous channel connecting said 130

- edges, an elevation on each edge of said wheel having an inclined portion leading from said chamfered edge to the top thereof, said incline being opposite and in alinement 5 with the openings into said channel, a driven member adapted to rotate in the plane of the axis of the driving member, radial pins extending from the periphery thereof and adapted to bear on said chamfered edges, 10 and means located between the pins of the driven member and chamfered edges of the driving member to hold the driven member from movement except at predetermined intervals.
- 15 6. In a mechanical movement a driving member, comprising a disk having chamfered edges and provided with a sinuous groove extending across the face thereof, a driven member comprising a disk adapted 20 to rotate in the same plane as the axis of the driving member, radial pins extending from the periphery of the driven member and adapted to contact with the aforesaid chamfered edges and means for causing said pins 25 to enter said groove said driving and driven members being further provided with locking means consisting of a circumferential guide rotating with the driving member and a longitudinal guide rotating with the 30 driven member and coacting with the circumferential guide for holding the driven member against rotary movement at times when not being rotated.
7. In a mechanical movement a driving member, comprising a disk having chamfered edges and a circumferential, peripheral groove and provided with a sinuous groove connecting said edges, a driven member comprising a disk adapted to rotate in 35 the plane of the axis of the driving member, radial pins extending from the periphery of the driven member and adapted to contact said chamfered edges and to be engaged by said sinuous groove and means for causing 40 said pins to enter said sinuous groove, said driving and driven members being further provided with locking means consisting of a circumferential guide rotating with the driving member and a longitudinal guide 45 rotating with the driven member and coacting with the circumferential guide for holding the driven member against 50 rotary movement at times when not being rotated.
- ing the driven member against rotary movement at times when not being rotated.
8. In a mechanical movement a driving member, comprising a peripherally grooved 55 wheel provided with chamfered edges and having a sinuous channel connecting said edges, an elevation on each edge of said wheel having an inclined portion leading from said chamfered edge to the top thereof, 60 said incline being opposite and in alinement with the openings into said channel, a driven member adapted to rotate in the plane of the axis of the driving member, radial pins extending from the periphery thereof and 65 adapted to bear on said chamfered edges, said driving and driven members being further provided with locking means consisting of a circumferential guide rotating with the driving member and a longitudinal guide 70 rotating with the driven member and coacting with the circumferential guide for holding the driven member against rotary movement at times when not being rotated.
9. The combination of a driving member 75 and a driven member disposed at right angles thereto, the driven member being provided with radial pins, the driving member having inclined bearing faces against which said pins are adapted to bear, said faces 80 lying in planes parallel with the axes of the pins bearing thereon, a sinuous groove extending across the periphery and opening on said bearing faces, a radial elevation on each edge, inclines leading to said elevation and 85 adapted to cause the pins to enter said groove, said driving and driven members being further provided with locking means consisting of a circumferential guide rotating with the driving member and a longitudinal guide 90 rotating with the driven member and coacting with the circumferential guide for holding the driven member against 95 rotary movement at times when not being rotated.
- In testimony of which invention, we hereunto set our hands.
